UNITED STATES PATENT OFFICE.

SIMEON S. JACKSON, OF BOSTON, MASSACHUSETTS, ASSIGNOR, BY MESNE ASSIGNMENTS, TO THE STAFFORD COMPANY, OF READVILLE, BOSTON, MASSACHUSETTS, A CORPORATION OF MASSACHUSETTS.

FILLING-FEELER MECHANISM FOR LOOMS.

Application filed October 30, 1920. Serial No. 420,658.

To all whom it may concern:

Be it known that I, SIMEON S. JACKSON, a subject of Great Britain, residing at Hyde Park, Boston, in the county of Suffolk, State 5 of Massachusetts, have invented a certain new and useful Improvement in Filling-Feeler Mechanisms for Looms, of which the following is a specification, reference being had therein to the accompanying drawings.

10 The invention has relation to the so-called filling-feeler mechanisms which are employed in looms for the purpose of detecting when the shuttle-contained supply of weft or filling has become depleted to the 15 predetermined extent, and thereupon bringing about action to forestall delivery of the last end of the said supply from the shuttle, so as to avoid production of a short pick in the cloth being woven, which would render 20 the cloth defective.

A filling-feeler mechanism comprises, ordinarily, a weft or filling-feeler, and in conjunction therewith devices which under the governance of the filling-feeler are instrumental in bringing about the action aforesaid, (in some cases automatic replenishment of the weft-supply; in others, stoppage of the 25 loom), and a so-called controller located intermediate the filling-feeler and the said 30 devices, itself governed by the filling-feeler, and in turn controlling the said devices.

The invention is applicable to filling-feeler mechanisms of the class provided with side-slipping feeler devices, i. e., feeler devices characterized by a laterally-movable 35 feeler member which, by engagement of the shuttle-contained supply of weft or filling therewith at the time of each successive feeling action, is held from lateral movement, 40 that is to say is held from movement longitudinally of the weft or filling-carrier occupying the shuttle, until the remaining portion of the said supply is too small to prevent such movement, at which stage in the 45 depletion of the supply the laterally-movable feeler member is displaced in the direction of the length of the shuttle-contained weft or filling-carrier at the time of a feeling action and as a result of such displacement 50 the change is called. The general class of side-slipping feeler devices comprises two types of such devices, to either of which the present invention is applicable. These two types are, first, the type in which the tend-

ency of the feeler member to slip or move laterally results from forwardly-directed contact-pressure acting against a laterally offset feeling end or tip; and second, the type in which the tendency of the feeler member to move laterally is due to the application 60 of the yielding force of a spring or other convenient means at the time of the feeling action.

The general object of the invention is to provide improved means for operatively 65 combining and connecting together a side-slipping feeler device which moves forward and rearward in the feeling action, and a controller for the devices through which a change is called in the action of the loom. 70

The invention consists in connecting and combining means comprising, essentially, a lever which is operatively engaged with the controller, and a link which constitutes a direct connection between the lever and the 75 feeler member and swings in unison with the reciprocating forward and rearward movements of the latter, and through which the feeler member in slipping sidewise actuates the lever to bring about the action of the 80 controller by which the devices through which the change is called are made operative to call a change.

The drawings show an illustrative embodiment of the invention in a form of 85 feeler-mechanism having a side-slipping feeler device of the type first mentioned. The application of the features of the invention in connection with feeler devices of the second type referred to will be obvious to 90 those skilled in the art.

In the drawings,—

Fig. 1 is a top view of certain parts at one side of a loom, including a side-slipping filling-feeler of the first type, mounted in operative position upon its stand at the corresponding end of the breast-beam, the parts being shown in their normal positions.

Fig. 2 is a partly sectional side elevation of the said parts. 100

Fig. 3 is a front view of the feeler device and associated parts, and their supports, of Figs. 1 and 2.

The different views of the drawings show only small portions of the breast-beam 1 and 105 lay-beam 2 of a loom, 3 being the front-plate of the shuttle-box upon the end of the latter which is adjacent the feeler-mechanism, and

- 4 a shuttle occupying the said shuttle-box. The said front-plate and the front-wall of the shuttle have the usual openings 3^a, 4^a, to permit entrance of the contact-portion or tip 5 11 of the feeler device as the lay beats up, to provide for contact between the said contact-portion or tip 11 and the filling-mass 6 upon the filling-carrier 7 occupying the shuttle.
- 10 The feeler device shown in the drawings comprises, as heretofore in some cases, a carrier-member 8 that is movable forwardly and rearwardly in the loom, and a feeler member 9 that is mounted upon a pivotal 15 stud 10 on the said carrier-member with capacity for transverse movement in a horizontal plane and has a rearwardly projecting contact-portion 11, the filling-engaging end 11^a of which is offset laterally with relation to the pivot of the feeler member. To 20 this lateral offsetting is due the tendency of the feeler member to swing around its pivot under the forwardly acting pressure of the shuttle-contents against its contact-portion 25 in a feeling action.
- The carrier-member 8 is in the usual form of a slide working in a guideway at 12^a upon a small stand 12 attached to the outer end of a main supporting stand 13 extending 30 outward from the breast-beam. A forwardly-extending reduced extension 8^a of the slide works in a hole through an upstanding portion 12^b of the forward part of stand 12. A cap or cover-plate 12^c, bridging 35 the guideway and holding the slide down therein, is secured in place by screws 12^d, 12^e. Other forms of carrier-member and supporting means therefor known in the art are adapted to be employed.
- 40 The spring-tension by which the carrier-member is held normally in its rearward position, and by which it is returned to that position after having been pushed forward in a feeling action by the pressure of the 45 shuttle-contents against the end 11^a of the feeler member, is applied by means of an expanding spiral spring 8^b surrounding the reduced forward extension of the slide between the body of the slide and the upstanding portion 12^b of stand 12. The spring, 50 as usual, yields to permit the forward movement of the feeler device that is caused by pressure of the shuttle-contained filling-mass against the filling-engaging end or tip of the 55 feeler member at the time of a feeling action, and then returns the feeler device rearwardly to its normal position as the lay moves rearwardly.

The controller of this embodiment of the 60 invention is of the preferred form, namely a rocking controller comprising a rockshaft 14 that is journaled in bearings 14^a, 14^b, with which the main supporting stand 13 is provided, and an arm 15 fixed upon the 65 inner end of the said rockshaft and connect-

ing with the devices through which a change in the operation of the loom is called. The said rockshaft extends in a transverse direction from the outboard position which the filling-feeler is required to occupy to the 70 inboard position of the devices through which a change is called, with its outer end operatively related with the filling-feeler devices and its inner end operatively related by means of the arm 15 with the devices by 75 which the change is called. The drawings show the latter devices as of customary character comprising a latch or dog 18 pivotally connected with an upstanding arm 19 of the usual controlling rockshaft 20, the 80 said controlling rockshaft 20 in practice being connected operatively with the replenishing or stopping instrumentalities of the loom. In this instance the arm 15 carries a pin 16 which works in a slot 17 extending 85 lengthwise of the latch or dog 18. The engagement of the tooth 18^a of the latch or dog 18 by the shoulder 21^a of the vibrating weft-hammer or gooseneck 21 is controlled through the agency of the rocking controller. 90 Normally, the controller holds the latch or dog clear of the path of the shoulder 21^a. This result is secured in the present instance through the action of a spiral spring 22, surrounding the controller-rockshaft and 95 having one end thereof engaged with the adjacent stand-bearing 14^a and the other end engaged with a collar 23 fixed by means of a binding screw 24 upon the controller-rockshaft. The said spring operates torsionally 100 with a tendency to keep the controller-rockshaft rocked into a position in which its arm and pin hold the latch or dog 18 elevated clear of the moving weft-hammer or gooseneck. The tension of the spring may 105 be varied by adjustment of the collar around the rockshaft. Other arrangements of devices in connection with a controller, for calling a change, are known in the art. Referring now to the link 30 and lever 28 by 110 which according to the present invention the side-slipping feeler member and the rocking controller are operatively combined and connected with each other,—

The link extends transversely of the loom 115 from the side-slipping feeler member to the lever and is engaged with the latter at a point at one side of the said feeler-device. The lever engages with a projecting arm or finger 25 carried by the controller-rockshaft. 120 Normally, the tension of the controller-spring 22, acting with a tendency to rock the controller, causes arm or finger 25 to act upon lever 28 so as by end-thrust of the link 30 to hold the feeler member laterally 125 in its presentation-position, which in this instance is determined by a stop 9^b upon carrier 8.

In the illustrated embodiment, the outer end of the link is connected pivotally to an 130

arm or crank 9^a of the feeler member, located in front of the pivot 10 of said member, so that the said end-thrust tends to turn the feeler member around its pivot 5 until the said arm or crank makes lateral contact with stop 9^b.

The link 30 swings idly forward and rearward around its point of pivotal connection with the arm 28^b of the lever in the feeling actions during the normal working of the feeler-device prior to substantial exhaustion 10 of the shuttle-contained supply of weft or filling. It is of sufficient length to permit the forward and rearward working strokes 15 of the feeler-device, caused by the contact of the shuttle contents with the contact-portion or tip 11 of the feeler-device, to take place without any or material swinging movement of the lever 28, and consequently without 20 causing the controller-rockshaft to turn so as to permit the latch or dog 18 to become engaged by the weft-hammer or gooseneck 21. When, however, sidewise movement of the 25 feeler-member is produced in consequence of the depletion of the supply or weft or filling within the shuttle, this movement transmitted through the link 30 to the lever 28 turns the latter around its pivot sufficiently to actuate the controller so as by the rock- 30 ing movement of the latter thereby produced to place the latch or dog 18 in position to be engaged by the shoulder 21^a of the weft-hammer or gooseneck. Through such engagement, the latch or dog is moved and 35 the rockshaft 20 is rocked so as to call a change in the working of the loom.

As will be apparent from the foregoing, the connections comprising the lever 28 and the link 30 extending transversely between 40 the said lever and the pivoted feeler member not only enable the spring 22 surrounding the controller-rockshaft to hold the feeler member normally in its regular presentation position, but also serve to enable the feeler 45 member to actuate the controller so as to rock the latter to call a change in the working of the loom when sidewise movement of the feeler-member takes place in a feeling action.

50 In this embodiment of the features of the invention, the lever 28 is arranged to swing in a horizontal plane around its pivot 29, which is a screw that passes through an inward extension of cover-plate 12^c into the 55 outer portion of stand 15, and the arm or finger 25 projects upwardly from the controller-rockshaft 14, the arm 28^a of the lever being extended transversely outward for engagement with the forward side of the said 60 arm or finger 25, and the second arm 28^b being extended rearward from the pivot of the lever.

I have shown and described the best form 65 of embodiment of the features of the invention that has thus far been devised by me,

but in practice the form and arrangement of parts may be varied more or less from what is shown in the drawings.

What I claim is,—

1. In a filling-feeler mechanism for looms, 70 the combination with a side-slipping feeler member that moves forwardly and rearwardly in the feeling action, devices that call a change in the action of the loom, and a controller for the said devices, of connecting and combining devices comprising, essentially, a lever which is operatively engaged with said controller, and a link between the lever and the feeler member which swings in unison with the reciprocating forward and rearward movements of the latter, actuated longitudinally by the feeler member in slipping sidewise and through such longitudinal movement actuating the lever to bring about the action of the controller 80 by which the devices through which the change is called are made operative to call a change.

2. The combination with a feeler-device comprising a side-slipping feeler member 90 which reciprocates forwardly and rearwardly in the feeling action, and a movable controller for the change-calling means, of a transversely-movable controlling lever for said controller, and a link extending transversely from said feeler member to said lever, pivotally connected with the lever at a point at one side of the feeler-device, swinging forward and rearward around said point in the normal working of the feeler-device, and in case of side-slipping of the feeler member moved endwise and thereby caused to actuate the said lever to bring about the calling of the change.

3. The combination with a feeler-device 105 comprising a side-slipping feeler member and a movable carrier therefor, and a movable controller for the change-calling means, of a transversely-movable controlling lever for said controller, and a link extending 110 transversely from said feeler member to said lever, pivotally connected with the lever at a point at one side of the feeler-device, swinging forward and rearward around said point in the normal working of the feeler-device, and in case of side-slipping of the feeler-member moved endwise and thereby caused to actuate the said lever to bring about the calling of the change.

4. The combination with a feeler-device 120 comprising a side-slipping feeler member which reciprocates forwardly and rearwardly in the feeling action, and a rocking controller for the change-calling means, of a transversely movable controlling lever for 125 said controller, and a link extending transversely from said feeler member to said lever, pivotally connected to the lever at a point at one side of the feeler-device, swinging forward and rearward around said point 130

in the normal working of the feeler-device, and in case of side-slipping of the feeler member moved endwise so as to actuate the said lever and thereby rock the controller to 5 call the change.

5. The combination with a feeler-device comprising a side-slipping feeler member and a movable carrier therefor, and a rock-ing controller for the change-calling means, 10 of a transversely movable controlling lever for said controller, and a link extending transversely from said feeler member to said lever, pivotally connected to the lever at a point at one side of the feeler-device, 15 swinging forward and rearward around said point in the normal working of the feeler-device, and in case of side-slipping of the feeler member moved endwise so as to actuate the said lever and thereby rock the controller to call the change.

6. The combination with a feeler-device comprising a side-slipping feeler member and a movable carrier therefor, and a movable controller for the change-calling means, 20 of a controlling lever for said controller transversely movable in a horizontal plane, and a link extending transversely from said feeler member to said lever, pivotally con-

nected with the lever at a point at one side of the feeler-device, swinging forward and 30 rearward around said point in the normal working of the feeler-device, and in case of side-slipping of the feeler member moved endwise and thereby caused to actuate the said lever to bring about the calling of 35 the change.

7. The combination with the rockshaft of a yieldingly-actuated controller forming an element of the devices for calling a change in the operation of a loom, and a feeler-de- 40 vice comprising a movable carrier-member and a side-slipping feeler member pivoted thereon, of connections through which said feeler member and the controller recipro-cally control each other comprising a hori- 45 zontally swinging lever engaging an arm upon said controller-rockshaft, and a trans-versely-extending swinging link connecting said feeler member to said lever.

In testimony whereof I affix my signature 50 in presence of two witnesses.
